(57) **CLAIM**

The ornamental design for a four wire electrical connector, as shown and described.

DESCRIPTION

FIG. 1 is a first top plan view of a four wire electrical connector showing my new design;
FIG. 2 is a second top plan view thereof, on a larger scale;
FIG. 3 is a first side view thereof;
FIG. 4 is a front view thereof;
FIG. 5 is a rear view thereof;
FIG. 6 is a bottom view thereof;
FIG. 7 is a second side view thereof;
FIG. 8 is a first perspective view thereof;
FIG. 9 is a second perspective view thereof;
FIG. 10 is a third perspective view thereof;
FIG. 11 is a fourth perspective view thereof;
FIG. 12 is a fifth perspective view thereof;
FIG. 13 is a sixth perspective view thereof;
FIG. 14 is a seventh perspective view thereof; and,
FIG. 15 is a eighth perspective view thereof.

All broken lines showing are included for the purpose of illustrating environment and form no part of the claimed design.
